CLAIM

The ornamental design for a gantry frame, as shown and described.

DESCRIPTION

FIG. 1 is a front, top perspective view of a gantry frame, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail “9” identified in FIG. 1;

FIG. 10 is an enlarged view of detail “10” identified in FIG. 1;

FIG. 11 is an enlarged view of detail “11” identified in FIG. 2; and,

FIG. 12 is an enlarged view of detail “12” identified in FIG. 2.

The dashed lines in the figures illustrate portions of the gantry frame that form no part of the claimed design. The dash dot dash lines in FIGS. 1, 2, 9, 10, 11 and 12 are for the purpose of illustrating the enlarged view indicators and form no part of the claimed design.

1 Claim, 12 Drawing Sheets
